UNITED STATES PATENT OFFICE.

OTTO KAMPFE, OF NEW YORK, N. Y.

DESIGN FOR A CIGAR-CUTTER.

41,433.

Specification for Design.

Patented June 6, 1911.

Application filed March 17, 1911. Serial No. 615,124. Term of patent 7 years.

To all whom it may concern:

Be it known that I, OTTO KAMPFE, a citizen of the United States, residing in the borough of Brooklyn, county of Kings, city and State of New York, have invented a new, original, and ornamental Design for Cigar-Cutters, of which the following is a specification, reference being had to the accompanying drawing, forming part thereof.

The figure is a perspective view of a cigar cutter, showing my new design.

I claim:

The ornamental design for a cigar cutter, as shown.

Signed by me this 9th day of March, 1911.

OTTO KAMPFE.

Witnesses:

GEO. T. PINCKNEY,
BERTHA M. ALLEN.
